UNITED STATES PATENT OFFICE

FRANZ KRUCKENBERG AND CURT STEDEFELD, OF HEIDELBERG, GERMANY

RAIL-BEARER STRUCTURE FOR HIGH-SPEED SUSPENDED RAILWAYS

Application filed March 5, 1927, Serial No. 173,197, and in Germany November 11, 1925.

In our United States Patent No. 1,659,322, February 14, 1928, there is described a rail track for the passage of high speed suspended trains, in which the running rails are unbroken over their whole length and made without unevennesses and held to a structure by horizontally movable or slidable carrier arms. The individual pieces of rail at the joints were either welded or pressed together to such an extent that gaps were in effect nonexistent.

If now instead of an expensive material which is practically indifferent to temperature changes, as for example 36% nickel steel (invar steel), the usual material with the usual co-efficient of expansion is used for the rails; the necessary structure for supporting such rails must be arranged in a particular way in order to prevent the stresses which are set up in the continuous rail by temperature differences, from producing such alterations in length of the rail as will endanger the security of operation and in particular in order to prevent any damage to the traffic in the event of a rail breakage due to a fault in the material.

Several measures are taken to accomplish this purpose as completely as possible. Since the whole rail structure rests on piers which support the main girders along which on each side is a running rail, the running rails in the first place are rigidly secured to the piers firmly anchored in the ground. If therefore the running rails run unbroken for several hundred kilometers and sustain at different points in the whole length different tensile or compressive stresses caused by temperature variations, all these stresses and differences in the various rail lengths are transferred to the firmly anchored piers. This transfer to the piers is further ensured by the so-called longitudinal rail carriers, which themselves support the lateral rail carriers and are so arranged that they can yield at their points of connection to the piers to compressive strains but can oppose a sufficient resistance to tension. The main girders are freely movable or extensible in the longitudinal direction between each two piers and are borne thereon, and are also connected at their mid-points in

a rigid manner with the rails and therefore with the longitudinal rail carriers, so that their mid-points are fixed in relation to the piers at each end by the running rails.

The arrangement which is described in detail below, allows security of operation to be achieved in the event of a rail breakage, in that it effectually prevents the formation of a large gap at a break in particular when considerable tensile stresses are called into play over the whole length of the rail owing to very low temperatures. The said arrangement also avoids buckling of the rails horizontally or vertically when high temperatures produce a compressive stress throughout the rails.

In the construction of the rail carrying structure, the mean temperature of 10-15° C. is assumed for the normal mean condition of the rails and longitudinal rail supports. The highest value, both of the compressive stress at the maximum temperature and of the tensile stress at the lowest temperature, which can occur is about 1,000 kg./sq. cm. which is quite inconsiderable in a material with a sufficiently high elastic limit.

The construction of the rail carrying structure in accordance with the invention and the manner in which the desired object is achieved, is explained below with reference to the accompanying drawings, in which

Fig. 1 is a perspective view of one side of part of the general rail system,

Fig. 2 is a plan view of one form of end connection of the main girder,

Fig. 3 is a side view of another form of end connection of the main girder,

Figs. 4 and 5 are respectively a detail cross section and a side view partly in section of the longitudinal rail carrier, showing the arrangement of the lateral rail carriers,

Fig. 6 is a side view of one form of end connection of the longitudinal rail carriers,

Figs. 7 and 8 are vertical transverse sections on lines A—A and B—B, respectively, of Fig. 1,

Figs. 9 and 10 are schematic diagrams illustrating the method of anchoring the rails at the piers, and at central portions of the spans, respectively.

Figure 1 shows the rail carrying structure with piers and one longitudinal rail carrier, on which one rail is secured. Obviously on the opposite side of the structure illustrated is another rail (not shown) with the longitudinal rail carrier appertaining thereto.

The rail supporting structure consists essentially of the main girders *a*, which are supported in the usual manner, longitudinally 10 slidable, on the piers *f* so that they can freely expand and contract with temperature changes. The longitudinal rail carrier *c* is articulated to the out-rigger arms *b* extending sideways in vertical planes. In the longitudinal rail carrier *c* are mounted lateral rail carriers *d* which are articulated at one end to the running rail *e*. These lateral carriers are provided at comparatively short intervals and are so connected to the longitudinal rail carriers *c* that they can swing in a horizontal plane. This connection is very simply effected by flat metal strips *q* which are secured between the upper and lower flanges *r* and *r'* of the longitudinal carriers *c* (Figures 4 and 5) 20 and on the middle parts of which are mounted the lateral carriers *d*. In this way the latter can yield to forces acting in the horizontal plane.

The rails are welded together at the joints 30 or are immovably clamped together.

The inner arms of the lateral carriers are articulated to the lower flange *z* of the main girders *a*. In addition the rail *e* is rigidly and immovably connected to the piers *f* of 35 the structure by a triangular construction *g* and with the girder *a* at the centre between two piers *f* by a triangular construction *h*.

The lateral rail carriers *d* can bend in relation to the rail *e* during the relative movement 40 of the main girders and the longitudinal carriers *c* caused by temperature changes, and in consequence no unpermissible stresses are transferred to the rails. If the lateral carrier *d* bends the band *q* twists slightly, little 45 resistance being offered to such twisting owing to the cross sectional form of the band. Only small forces produced by the changes in length of the main girder *a* and the longitudinal carrier *c* will therefore be transmitted 50 to the rail *e*.

The longitudinal rail carrier *c* is borne on the piers *f* at *i* in such a manner that it can expand with the temperatures higher than those prevailing when it was originally erected, so that compressive and buckling stresses 55 are not set up in it. The main girder *a* can also slide in the longitudinal direction on the piers *f*, so that in it also, no internal compression is set up. It can freely expand from the 60 centre point where it is rigidly secured to the rail *e* and longitudinal rail-carrier *c*, in either direction, being connected at each end to the pier for example by a spring system *w* or *l* or by a pendulum suspension *o*.

Figure 2 shows the arrangement of such a

spring system in plan. The sides *m*, *m'* of the main girder are articulated at the ends to a laminated spring *l*, pre-loaded to such an extent that the spring is always in a position to overcome the rolling friction of the longitudinally movable bearings *n* and *n'*. During 70 changes in length of the main girder the springs *l* at each end ensure its being held in the mid position and in this way no stress is produced in the rail by a change in position of the main girder *a*.

Another form of connection of the main girder *a* with the pier *f* is illustrated in Figure 3. Here the main girder *a* is held by the end of its lower flange by a suspender *o* which is secured to the pier *f* at *p* in a moment transmitting fashion.

With very low temperatures, tensile stresses occur in the rail. Since the rail on each side of the piers is securely connected to the piers, the rails over their whole lengths remain at rest. If with a high tensile stress a break occurs owing to faulty material, then the tension acting on one side in the rails of the neighbouring section will tend to twist the piers *f* 85 and a large gap, dangerous for the operation of the line, may be produced at the break.

In order effectively to prevent such gaps, which would render the safety of traffic doubtful, the bearing supports of the longitudinal rail carriers *c* on the piers *f* are so constructed that during temperature higher than normal they act as plain bearings permitting longitudinal movement, but at lower than normal temperatures, prevent such movements. This can be effected for example as shown in Figure 6. The longitudinal carrier *c* is borne on the pier *f* on a bearing *s* permitting longitudinal movement and is connected to the pier by short eye bars *t*, similarly to two members of a chain. In erecting the structure, the two eye bars are fully stretched but not tensioned. If the temperature rises above the temperature at the time of construction the longitudinal rail carrier *c* can freely expand with, and in the same manner as, the main girder *a*, since the eye bars, owing to the pivotal joints *u* and *u'*, cannot transmit compressive forces. On the other hand if the temperature falls below 100 the temperature at the time of construction the longitudinal rail carrier *c* is prevented by the eye bars *t* from contracting along with the main girder *a*. The same temperature 110 stresses will be set up as in the rail. Between 115 the piers *f* therefore the longitudinal rail carriers form positive tensile connections, which undergo smaller or greater tensile 120 stresses according to the temperature changes, for example at -30° C. and an erecting temperature of 10° to 15° C., about 1,000 kg./sq. cm. If now a rail breaks, for example at *v*, then the tension acting on the now free 125 rail ends, will be transmitted to the longitudinal rail carriers *c* at the rigid connections 130

h of the rail *e* thereto. These longitudinal carriers are so connected to one another over the piers by suitably constructed members *i* that they act at low temperatures, as tension members which by being given a suitable cross section can easily take over the extra load due to rail tension in the event of a rail breakage. Owing to the comparatively large cross sectional area of the longitudinal carriers *c* in comparison with the rail cross sectional area, the stress intensity (in kg./sq. cm.) in the carriers is not much increased. No perceptible twist of the piers *f* takes place, so that the only factor tending to open the gap produced by the break will be the contraction due to low temperature of the free rail ends from *v* to the nearest fixed holding point *g* or *h*. This is so small as to be allowable in practical operation.

If the temperature rises above the temperature at the time of construction, then, since they cannot expand, a compressive stress is set up in the rails. At 60° C. this reaches a value of about 1,000 kg./sq. cm., which in a material with a sufficiently high elastic limit for sustaining the stresses caused by the train loads and so forth, is but slight. At the same time with this compressive stress there is the risk of buckling. This is met by firmly holding the rails both in the horizontal and vertical planes by the lateral carriers *d* at as short intervals as possible. Owing to the short free buckling lengths thus produced and the relatively large resisting moment of the rail, the security against buckling is very high.

What we claim is:—

1. A rail supporting structure for high speed suspended railways having a substantially continuous welded trackway formed of jointed rails, characterized in that the rails are immovably fixed to the piers firmly enclosed in the ground, and to an intermediate portion of the supporting structure spanning the gap between adjacent piers.
2. A supporting structure for high speed suspended railways having a jointed but substantially continuous trackway, comprising spaced piers firmly anchored to the ground, supporting structures between adjacent piers, means for supporting the trackway from said structures at a plurality of points between adjacent piers, and means for immovably fixing said trackway to said piers and to the middle of each of said supporting structures.
3. A rail supporting structure for high speed suspended railways, having a substantially continuous welded trackway formed of jointed rails, characterized in that the rails are immovably fixed to piers firmly enclosed in the ground and to an intermediate portion of the supporting structure spanning the gap between adjacent piers, wherein the lateral supports which hold the rail are supported on a longitudinal rail carrier, and the longi-

tudinal rail carriers, supported by out-rigger arms on main girders, are connected to one another at the piers by members which transmit only tensile stresses.

4. A rail supporting structure according to claim 3, characterized in that both the rails and their lateral carrier supporting longitudinal carrier, are immovably secured to the middle of the main girder carried between two piers.

5. A rail supporting structure according to claim 3, characterized in that the main girders are longitudinally movably supported at each end on the piers.

6. A rail supporting structure according to claim 3, characterized in that the main girders are borne at each end by a spring suspension or other spring system in order to centre them.

7. A rail supporting structure according to claim 3, characterized in that the lateral rail carriers are connected to the longitudinal carriers so that they can swing in the horizontal plane.

8. A rail supporting structure according to claim 3, characterized in that the lateral rail carriers are of two armed form, and are pivotally connected by one arm with the rail and by the other arm with the main girder.

9. A rail supporting structure according to claim 3, characterized in that the joint between the lateral rail carrier and the longitudinal rail carrier is formed by a constructional member of such cross section as will allow it to yield rotationally.

In testimony whereof we affix our signatures.
